UNITED STATES PATENT OFFICE

HARRY H. FLEER, OF QUINCY, ILLINOIS, ASSIGNOR TO THE EUREKA STEEL RANGE CO.,
OF ST. CLAIR COUNTY, ILLINOIS, A CORPORATION OF ILLINOIS

DESIGN FOR A COOKING STOVE

Application filed February 18, 1933. Serial No. 47,254. Term of patent 3½ years.

To all whom it may concern:

Be it known that I, HARRY H. FLEER, a citizen of the United States, and a resident of the city of Quincy, county of Adams, and State of Illinois, have invented a new, original, and ornamental Design for a Cooking Stove, of which the following is a specification, reference being had to the accompanying drawing, forming part thereof.

In the drawing, Fig. 1 is a perspective view of a cooking stove embodying my new design, and Fig. 2 is a fragmentary plan view of the front portion thereof.

I claim:

The ornamental design for a cooking stove, substantially as shown.

HARRY H. FLEER.
